(57) **CLAIM**

The ornamental design of a ratchet release button, substantially as shown and described.

DESCRIPTION

FIG. 1 is a perspective view of a ratchet release button embodying the design of the present invention, a tool being illustrated in phantom.

FIG. 2 is a right side elevational view of the ratchet release button illustrated in FIG. 1.

FIG. 3 is a left side elevational view of the ratchet release button shown in FIG. 1.

FIG. 4 is a top view of the ratchet release button shown in FIG. 1.

FIG. 5 is a bottom view of the ratchet release button shown in FIG. 1.

FIG. 6 is a front side elevational view of the ratchet release button illustrated in FIG. 1; and,

FIG. 7 is a back side elevational view of the ratchet release button illustrated in FIG. 1.
